UNITED STATES PATENT OFFICE.

GEORG GUNDERMANN, OF BROOKLYN, NEW YORK.

FAUCET.

1,206,533.

Specification of Letters Patent. Patented Nov. 28, 1916.

Application filed August 11, 1916. Serial No. 114,345.

To all whom it may concern:

Be it known that I, GEORG GUNDERMANN, a subject of the Emperor of Germany, and a resident of Brooklyn, in the county of 5 Kings and State of New York, have invented certain new and useful Improvements in Faucets, of which the following is a specification.

This invention relates to faucets, or the 10 like, particularly of the type used in drawing liquids from barrels and kegs, and has as one object, to provide devices of this character with a locking mechanism which will prevent unauthorized persons from 15 tampering with the same during the temporary absence of the operator.

Another object of this invention is to provide devices of this character, simple in 20 their construction, strong, durable, efficient 25 in use, comparatively cheap to manufacture and which may be readily operated.

With these and other objects in view this invention consists of a novel construction, combination and arrangement of parts here- 25 inafter described and illustrated in the accompanying drawing, in which:—

Figure 1 is a side elevation of my invention as applied to faucets. Fig. 2 is a vertical longitudinal sectional view through the 30 same, showing the key in dotted lines ready to be inserted into the lock. Fig. 3 is an enlarged transverse sectional view taken on line 3—3 of Fig. 2. Fig. 4 is a perspective view of the key supporting member, and 35 Fig. 5 is a bottom plan view of the lock casing.

Referring to the drawing, the faucet embodies a body portion 10, having a substantially vertical tapered opening 12 which 40 communicates with a longitudinally extending inlet 13. The turning plug 14 of the faucet is substantially conoidal in contour, conforming to the shape of the vertical tapered opening 12 which is formed in the 45 body portion 10, and is of such diameter as to snugly fit the opening but turn freely within. The plug 14 is provided with an outlet port or passage 15 which is registerable with the inlet 13 whereby the flow of 50 the liquid may be regulated. The upper end of the turning plug 14 is provided with a stem 16 which is cut away leaving an upwardly extending arm 18 having formed at one end a circular bearing plate 20 having 55 a metal cover and provided with an opening in which a rod 21 is inserted ex-

tending down into a threaded recess 22 of the stem 16. On each side of the stem 16 is formed recesses in which is adapted to slide a key supporting member. This key 60 supporting member is made of one piece of sheet metal having two side members 24—25 adapted to slide in the recesses formed in the stem 16, an apertured transverse portion 26 through which extends the rod 21 and 65 outwardly extending key supporting portions 27, having their ends turned up as at 28 and 45. A spring 17 is interposed between the transverse portion of the key supporting member and the end of the stem 70 16, which normally holds the key supporting member in a raised position, the bearing plate 20 forming a stop to prevent any further movement.

A cylindrical casing 30 covering the locking mechanism and also giving a good appearance to the faucet, has a flange 31 which is secured to a flange 32, formed on the body portion 10 by means of stub belts 33. The inner face of the casing 30 is provided with 80 two recesses 43 and 44 into which extend the ends 28 and 45 of the key supporting member which holds the turning plug in a locked position. The ends 28 and 45 are of different size being suited to the opening 85 43 and 45 respectively so as to insure correct positioning of the parts; this arrangement also compels the correct re-disposition of parts and full turn of the plug before 90 unlocking can again take place.

A key 34, which has a cylindrical portion 35, is adapted to fit over the stem 16 and has provided on each side thereof slots 37 which are adapted to slide over lugs 38 formed on the stem 16. A cover 39 pivoted 95 to the casing 30 covers the opening formed therein to prevent dirt and other foreign matter from falling into the locking means.

It will be seen from the foregoing that when it is desired to unlock and turn the 100 plug so that the outlet port may communicate with the inlet branch, the key is placed over the stem and the lugs 38 engage the slots 37, the end of the key resting on the members 28 and 45, and by pressing down 105 on the same the ends of the key supporting members are pushed down out of engagement with the recess 44 and 45, formed in the casing, thereby unlocking the same which will then allow the plug to turn freely 110 and by reversing the operation, the plug will be locked again.

Having thus described my invention what I claim and desire Letters Patent on is:—

In a faucet comprising a casing having an inlet opening, a turning plug mounted

5 in said casing having an opening registerable with the said inlet opening, a stem extending from said plug having a recess formed therein, a spring-pressed locking member mounted in said recess, lugs on said

10 stem, a casing covering said stem and secured to said faucet, the casing having re-

cesses formed therein to receive the ends of said locking member, and a key having a cylindrical portion fitting over said stem and resting on said locking member, said key having slots formed therein which receive said lugs.

Signed at New York, in the county of New York, and State of New York, this 22nd day of July, 1916.

GEORG GUNDERMANN.
